UNITED STATES PATENT OFFICE.

CHARLES W. CARSON, OF ST. JOSEPH, MISSOURI, ASSIGNOR OF ONE-THIRD TO EUGENE V. WHITE AND ONE-THIRD TO FRANK F. HARL, OF ST. JOSEPH, MISSOURI.

CUTTING APPARATUS FOR HARVESTERS.

No. 892,028.

Specification of Letters Patent.

Patented June 30, 1908.

Application filed July 26, 1907. Serial No. 385,688.

To all whom it may concern:

Be it known that I, CHARLES W. CARSON, a citizen of the United States, residing at St. Joseph, in the county of Buchanan and State of Missouri, have invented new and useful Improvements in Cutting Apparatus for Harvesters, of which the following is a specification.

This invention relates to cutting apparatus for harvesters, and it has for its objects to simplify and improve the construction and operation of this class of devices, and particularly to provide an improved construction whereby the knives or cutters may be secured upon the cutter bar in such a manner that they will be held with absolute security against displacement, and at the same time in such a manner that any one of the blades or cutter sections may be readily detached at any time without disturbing the remaining blades, or the means whereby such blades are secured, for the purpose of repairing breakage or when, for any reason, it shall be desired to remove the blades.

25 A further object of the invention is to improve and simplify the connection of the ledger plates with the guard fingers.

With these and other ends in view which will readily appear as the nature of the invention is better understood, the same consists in the improved construction and novel arrangement and combination of parts which will be hereinafter fully described and particularly pointed out in the claims.

35 In the accompanying drawings has been illustrated a simple and preferred form of the invention; it being, however, understood that no limitation is necessarily made to the precise structural details therein exhibited, 40 but that changes, alterations and modifications within the scope of the invention may be resorted to when desired.

In the drawing, Figure 1 is a top plan view, partly in section, of a portion of a cutting apparatus constructed in accordance with the invention. Fig. 2 is a longitudinal vertical sectional view taken on the plane indicated by the line 2—2 in Fig. 1. Fig. 3 is a vertical sectional view taken on the plane indicated by the line 3—3 in Fig. 1. Fig. 4 is 50 a perspective view showing one of the improved knives or cutters, detached.

Corresponding parts in the several figures are denoted by like characters of reference.

55 The improved knife or cutter blade 1 is

provided near the rear edge thereof with a rectangular aperture 2; said blade which is formed in the usual manner with a straight rear edge 3, with parallel side edges 4—4 adjacent to the rear edge, and with beveled forwardly inclined cutting edges 5—5, is provided at one of its side edges with a laterally extending lug 6 of rectangular shape, and at its opposite side edge with a correspondingly shaped notch or recess 7.

60 The cutter bar 8 is provided upon its upper side with suitably spaced lugs or projections 9 of rectangular shape, and of suitable size to fit accurately in the rectangular apertures 2 of the knives or blades; said lugs or projections being so spaced that when the blades are placed in engagement therewith the side edges of said blades will accurately abut upon or contact with each other, the projecting lug 6 of each blade entering into engagement 70 with the notch 7 in the side wall of an adjacent blade, thus securely interlocking the blades and reinforcing them against displacement.

75 The cutter bar is provided with preformations 10 registering with and extending through the upwardly projecting lugs 9, said perforations being provided with internally threaded bushings, for the reception of bolts or connecting members 12. The knives or 80 blades are secured in position, in pairs, by means of straps 13 each of which is provided adjacent to the ends thereof with apertures 14 for the passage of the fastening screws or bolts 12. It will be readily seen that by the 85 application of the straps 13, the blades or cutters will be secured very firmly in position, but in such a manner that any one of the blades may be readily detached by simply removing the bolt or fastening screw passing 90 therethrough, when the strap 13 may be swung to one side out of the way, thus permitting the blade to be lifted from its position. The pair of blades nearest adjacent to the inner end of the cutter bar may be appropriately secured in position by means of the knuckle plate 16 having the post or standard 17 forming the bearing for the pitman, not shown, whereby the cutter bar is in practice operated.

100 The guard fingers 18 are to be bolted or secured in the usual manner upon the finger bar, not shown, and said guard fingers are provided near their forward ends with notches or recesses 19 for the reception of 110

lugs 20 projecting at the forward ends of the ledger plates 21 which latter are provided near their rear ends with countersunk perforations for the passage of stud bolts 22 whereby said ledger plates are secured in position upon the finger bars.

From the foregoing description taken in connection with the drawings hereto annexed, the operation and advantages of this invention will be readily understood by those skilled in the art to which it appertains. The construction is simple and inexpensive, and the knives or blades will be firmly secured, by the means described, upon the cutter bar, in such a manner that any one of said knives or blades except those adjacent to the knuckle plate 16 may readily be detached at any time, by simply removing one of the screws or fastening members 12, and swinging the strap 13 out of the way to one side to a position indicated in dotted lines in Fig. 1 of the drawing. The blades adjacent to the knuckle plate are less exposed to wear and injury than the remaining blades, and they do not often have to be removed but their removal may be readily effected by detaching the said knuckle plate. The ledger plates are likewise readily accessible, and any one of said ledger plates is readily removable by detaching the single screw or fastening member 22 whereby it is secured.

Having thus fully described the invention, what is claimed as new is:—

1. In a cutting apparatus for harvester, a knife or cutter blade provided near its rear edge with a rectangular slot, and having parallel side walls, one of which is provided with a laterally extending rectangular lug and the other with a correspondingly shaped notch or recess, in combination with a cutter bar having upward extending rectangular lugs accurately fitting the slots of the blades and apertures extending through said lugs, straps connecting the blades, in pairs, and having perforations adjacent to their ends, and fastening members extending through the perforations of the straps and through the apertures of the cutter bar.

2. In a cutting apparatus for harvester, a cutter bar having upward extending lugs, knives or blades having lug receiving apertures and provided with interengaging notches and laterally extending lugs, straps superposed upon the blades and connecting the latter in pairs, and fastening members extending through said straps and through the cutter bar and the upward extending lugs of the latter.

In testimony whereof, I affix my signature in presence of two witnesses.

CHARLES W. CARSON.
